Primary Examiner — Nathan M Johnston

(74) *Attorney, Agent, or Firm* — Nitin Kaushik

(57) **CLAIM**

The ornamental design for a toilet brush and holder, as shown and described.

DESCRIPTION

FIG. 1 is a top perspective view of its component 1, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof of its component 2;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is an enlarged plan view of its top surface;

FIG. 16 is an enlarged plan view of its bottom surface;

FIG. 17 is its combined state diagram; and,

FIG. 18 is an enlarged detail view of area 18 in FIG. 9. The broken lines in the drawings illustrate the portions of the toilet brush and holder, which form no part of the claimed design.

The dash-dot-dash broken lines encircling the enlarged views are for annotative purposes only and form no part of the claim thereof.

1 Claim, 18 Drawing Sheets
